MACHINE FOR GRINDING

Ralph W. Osbern, Muskegon, Mich., assignor to
 Johnson Products, Inc., Muskegon Heights,
 Mich., a corporation

Application April 7, 1939, Serial No. 266,602

9 Claims. (Cl. 51—100)

My invention relates to a method of grinding and a machine for accomplishing this method and more particularly to a method wherein a variety of shapes may be ground on the ends of valve 5 tappets of various shapes and sizes.

One of the problems encountered in present day grinding and finishing is the uneven wearing away of the abrasive wheel with the attendant necessity of then suspending operation in order to 10 true the wheel to its initial shape. This problem is a serious one for several reasons. First, the gradual wearing away of the most used part of the wheel results in the gradual production of work which may be below standard. Second, 15 valuable production time is lost during the operation of trueing the wheel.

My invention overcomes the above problems inasmuch as there is an even and gradual grinding entirely across the wheel and of course the 20 revolving of the wheel wears it away circumferentially at an even rate. Thus the wheel does not wear down at any one spot or place but wears evenly and consequently a minimum dressing thereof is required. As a matter of fact, the 25 movement of the points of grinding contact across the wheel are in a straight line and thus any high points which might form or tend to form are cut away by the actual grinding of the work itself upon succeeding operations.

30 Another very material advantage is that the grinding occurs at only a point and thus the cooling thereof is facilitated. This is true even though a flat surface is being ground or finished. If a flat surface were produced by a flat contact 35 obviously the central portions are more or less inaccessible either by air or cooling fluids and the heating problem comes to the fore. In my novel method this problem is automatically solved.

Another important advantage is that the machine 40 may be used to grind a variety of shapes merely by changing cams. This feature makes it possible for one machine to take the place of several machines that will grind only one or two shapes.

45 For the purpose of illustrating my invention I have shown in the accompanying drawings one form thereof, this form giving satisfactory and reliable results in practice, although it is to be understood that the various instrumentalities of 50 which my invention consists, and by use of which the desired method practiced, can be variously arranged and organized and that my invention is not limited to the precise arrangement and organization of the instrumentalities as herein shown and described.

In the drawing—

Fig. 1 is a side view of my invention, parts being broken away in order to expedite the showing.

Fig. 2 is a plan view of the machine shown in Fig. 1, parts likewise being broken away to expedite and clarify matters. 5

Fig. 3 is a fragmentary sectional view taken along the plane of the line 3—3 of Fig. 1.

Fig. 4 is a fragmentary sectional view taken along the line 4—4 of Fig. 2. 10

Fig. 5 is a diagrammatic view, in plan, illustrating the path of movement of an article relative to a finishing or roughing wheel.

Fig. 6 is a full size diagrammatic plan view disclosing the various steps in the grinding operation when grinding a flat surface or a conical 15 surface on the end of a tappet or similar piece.

Figs. 7, 8 and 9 are side views of three different shapes which may be produced in accordance with this invention. 20

Fig. 10 is a full size diagrammatic plan view illustrating the steps in the production of a tappet or the like having a spherical end and the shape of the cam needed to produce the same. 25

Fig. 11 is a sectional view taken along the plane of the line 11—11 of Fig. 10.

Fig. 12 is a sectional view taken along the plane of the line 12—12 of Fig. 11.

As shown in Figs. 1 and 2, numeral 5 indicates a base or frame having a raised portion 6 provided with ways or grooves 7, one groove being shown in Fig. 3. 30

A subbase 8 has ribs 9 entering the ways 1 whereby the subbase can slide or reciprocate during the action of the machine as herein described. 35

The subbase 8 is grooved at 10 to receive ribs 11 which extend downwardly from the upper base 12.

This upper base or unit 12 has a fixed member 40 13, see Fig. 2, which rotatably receives the headed end of an adjusting screw 14 threadedly passing through an extension or lug 15 formed as one with the subbase 8.

The unit 12 has a shaft 16 which carries a 45 grinding wheel 17. The shaft and grinding wheel may be motor driven.

From the above construction it will be understood that normally the upper unit 12 is rigid with the subbase 8 which carries the same but 50 that adjustment may be made therebetween by rotation of the threaded screw 14 in the desired direction in order to properly position the periphery of the grinding wheel relative to the work which is being ground. For instance, adjust- 55

ment of these members may be made when the chosen cam from the group of cams is initially inserted and also adjustment may be made to compensate for grinding wheel wear.

5 As shown in Figs. 1 and 2, a boss 18 extends rearwardly from the sliding base 8. A wall 19 extends upwardly from the base 5 and receives a spring plunger assembly now to be described. This spring means causes engagement between 10 the cam and its follower as will be readily understood as the description proceeds.

The wall 19 has a threaded opening 20 therein. A hollow sleeve 21, exteriorly threaded, is screwed to a desired position within the opening and a 15 lock nut 22 locks it into position. A coiled spring 23 is inserted within the hollow sleeve and a slideable plunger placed thereagainst. The outer end of the plunger, numbered 24, is urged against the abutment 18 and thus the entire assembly of the 20 sliding base 15, grinding wheel 17, and its prime mover are slid outwardly under controlled operation as will be described later. There may be one or more of the spring plunger assemblies.

An arm 26 extends upwardly from the sliding 25 base 8 and carries a seating recess formed by a rear wall 27 and end walls 28. Holes extend downwardly through the bottom of the recess and studs 30, one of these being shown in Fig. 1, thread 30 upwardly into the cam strip 31 and firmly hold it in position.

The cam strips 31 are interchangeable as desired and may be backed by shims of tapered or flat construction of various thicknesses as desired.

35 The base 5 is extended as shown and has a supporting and housing structure 35 shaped as shown to revolubly receive the trunnion 37 of the turntable 38. A track 40 is machined on the underside of the turntable and faces downwardly. A 40 second track 39 is formed upon the supporting structure 35 in opposed relationship to the track 40 and thus the table may be rotated in free and easy fashion.

The trunnion 37 of the turntable is provided 45 with a worm gear 41 driven by the worm 42 which in turn is driven by the motor 44 through suitable reduction gearing 43. Thus the turntable is caused to revolve slowly at the chosen speed, which speed may vary widely from even 1 to 12

50 R. P. M.

As shown in Figs. 1 and 2, work holders 45 are spaced upon the turntable 38 concentrically and motors 46 drive the chucks 47 therein by the belts 48. Thus the articles or tappets 50, see 55 Fig. 2, are rotated about their longitudinal axes as they are bodily moved or translated around the turntable circle. Bolts 51 hold the several units in place.

60 Directly below each unit, see Fig. 4, is a roller 52. A headed stud 53 extends centrally through this roller to serve as its axis and enters the lower side of the turntable at 54. A spacer 55 maintains the roller in proper position for contact with the chosen cam.

65 The start of this contact is indicated in Fig. 2. It will be apparent that rotation of the turntable 38 in the direction indicated by the arrow A causes movement of the sliding base 8 and the upper sliding base 12, which bases are kept integral, to the left against the action of the spring plunger 24. However, the work holder 45 and the work which it carries are also advancing to the left. The shape of the cam and its follower is so made as to have a slight or virtual engagement 70 during the entire travel of the rotating work across

the periphery of the grinding wheel. As shown in Fig. 2, the cam 31 has a raise 56 which becomes effective at the time when the center of the work alines with the terminal side of the wheel to elevate or withdraw the work from contact with the wheel.

As shown in Fig. 5, numeral 70 is a grinding wheel which may be a finishing wheel of three inches width, more or less. The center of the turntable is at 71, the roller is 72 and the tappet 10 is 59. An intermediate roller position is shown in dotted lines.

The advancement of the roller 72 towards the periphery of the grinding wheel is indicated by the numeral 73. Similarly, the advancement of 15 the work is designated by 74. As these distances are different it will be apparent that a cam surface is needed to cause proper movement of the related parts. Also, a cam is needed to withdraw the work from the wheel at the finish of 20 the grind to prevent the trailing half of the work from contacting the wheel after the cut or grind has been completed.

Referring now to Fig. 6, 50 indicates the work, 25 which may be a valve tappet, shown in five consecutive positions, namely, I, II, III, IV and V, these positions following one another in time sequence. And, actually, the cam, which is now to be described, causes the valve tappet, which is being ground, to pass through an infinite number of positions whereby the planes along which grinding occurs really become points and the loci of all these points is the resulting cutting curve or finished surface.

The work 50, when in I position, extends beyond the corner of the grinding wheel a slight distance as indicated by 75. This is the extra metal which is to be removed when making a flat cut-off as shown in Fig. 7. The point 76 is the point which first contacts the wheel.

The term WR designates the radius from this point 76 to the center of the grinding wheel. The line RI extends from the center of the first or I position of the tappet to the center of the turntable and the cam roller 52 is located on this 45 line. The cam roller when at this point is designated 52I and the center of the roller is 19. A tangent line is drawn next to the roller, this line representing the cam which is to be so positioned relatively to the roller. TI is this line. 50 For convenience in illustration the point PI is located to the left of TI and is the same point. That is, this point maintains the tappet with its point 76 as shown.

The curved line which passes through 19 is a 55 part of a circumference drawn with the center of the turntable as its center. It is marked RR.

As shown at the left of Fig. 6, the tappet or work moves upwardly to the II position. The line 80 indicates the edge of the grinding wheel 60 and the tappet is cut as indicated by this line 80 and the line 81 inasmuch as the tappet revolves about its longitudinal axis. In other words, an annulus having a cross section as shown at 82 is removed.

The radius RII corresponds to the second or II position just referred to and this radius crosses the roller radius at 110. The roller 5288 has the tangent TII thereagainst. The distance between this tangent and the tangent TI is represented 70 by the numeral 17. So the roller's point of operation moves towards the grinding wheel this amount.

Referring to the left part of Fig. 6, numeral 83 indicates the initial position of the periphery of 75

the grinding wheel. Line 80 indicates the second position to be attained. The distance to be moved is indicated between these two lines 80 and 83 and is distance 78.

5 Thus 78 minus 77 is the difference which gives the point PII. In other words, the cam must slightly increase the movement of the roller 52 in order that the grinding wheel 17 may be sufficiently retracted and grinding may not be unduly increased.

10 The tappet is next moved to position III. The periphery of the wheel must now be located at 84. The corresponding axis or radius RIII locates the roller center at III6 and the roller is 15 shown at 52III and the tangent at TIII. Numeral 35 indicates the shifting of the roller to the left from its initial position. However, the necessary movement is that of 86, namely the 20 distance between 83 and 84. Measuring this distance from the cam base line 87, one obtains the point PIII. Thus three points on the cam have been obtained.

25 The tappet is now moved to position IV and 88 shows the desired position of the grinding wheel, 89 being the distance the wheel must be moved from its initial position. RIV is the radius which crosses line 44 to give center IV6. The roller 52IV has the tangent TIV at its left and the distance 90 is the lateral movement of the roller. 30 The difference between distances 89 and 90 gives the distance of the desired point PIV from the cam base line 87.

35 The tappet now is moved upwardly to position V. The corresponding radius is RV and the point V6 is obtained as the center of the roller. 52V is the roller. TV is the tangent. The lateral shifting of the roller is indicated by the numeral 92. Numeral 91 is the cutting plane and the distance thereto from its initial position is indicated by 40 93. The difference between the distances 92 and 93 gives the cam height or the point PV. Thus the main part of the cam is obtained. The final portion of the cam is now slanted upwardly so as to quickly separate the tappet and the grinding 45 wheel but it must not be steep enough to interfere with the roller 52V, this being the roller in its final position.

50 The above operations will give a piece of work having its end flat, as shown in Fig. 7. However, it will be apparent that the cam might be so shaped as to make position IV the concluding one whereby the tappet is lifted from the wheel thereabouts, instead of at position V, and the finished piece of work will be shaped more or less as shown 55 in Fig. 9.

55 Referring now to Fig. 10, wherein a tappet or piece as shown in Figs. 8 and 12 is to be formed, 100 indicates the initial position of the tappet. The tappet extends slightly beyond the corner of 60 the grinding wheel as shown. The initial contact point is at 101. Radius 102 is from the center of the turntable (not shown) and curve 103 is the concentric path of the roller 52.

65 Thus 104 is the center of the roller, which roller is indicated by numeral 105 in this position. Point 106 may be assumed as the starting point of the cam.

70 The tappet is now assumed to be moved upwardly to 107 and the desired curvature at 108, although only a portion of this curvature has actually been ground at this point. A line, parallel to the initial periphery of the wheel 110, is drawn at 109 tangent to the curve and then a perpendicular 111 is erected. This gives the point of 75 tangency and it is at this point that the grind-

ing occurs at this particular instant. The distance 112 is the distance that the grinding wheel must retreat during this phase of the swinging movement of the tappet.

75 The radius 113 crosses the curve 103 to position the roller 114 with the center 115. The center 115 has shifted from its first position 104 to the left a distance indicated by numeral 116.

10 The next position of the tappet is at 117 and by plotting in the same manner as described the distance 118 is determined as is also the distance 119.

15 In the next position 120 the distances 121 and 122 are determined.

20 When the tappet reaches the upper position 15 wherein its axis, when prolonged, alines with the terminal side of the wheel, then 123 is the distance which must be taken care of by the movement of the cam and the roller. Distance 124 is the distance taken care of or compensated for by 25 the movement of the roller. The small distance *h* is the height of the crown of the tappet.

25 Numeral 31 is the cam having openings 129 and a base line 128. The point 106 is located upon the base line to start with. The difference between 30 112 and 116 gives the height of point 131 above the base line. Similarly, the difference between 118 and 119 locates the point 132.

30 The next point on the cam is located by the difference between 121 and 122 and is designated 133. Point 134 is located by the difference between 35 123 and 124.

35 The cam is next curved upwardly at 135 but this curvature should be less than the curvature of the roller in order to prevent the roller 35 from leaving the cam prior to the point 134. The cam has a terminal curve at 136 and a beginning curve at 137.

40 Fig. 11 indicates a sectional view which may be taken along the line 11—11 of Fig. 10, showing 40 that the work might be of many different shapes and sizes.

45 The operation of my invention will be apparent from the preceding description. The linear speed of the grinding wheel may be 4500 feet per minute, more or less. The tappets or pieces may be revolved at 1800 R. P. M., more or less. Both may be rotated downwardly as shown by the arrows at 150 in Fig. 10, or in opposite directions.

50 The advantages of this machine are many, the wheel may be dressed straight across or in the shape of an irregular or regular curve, the cam being varied to adapt the path of the work to the shape of the wheel. The cam also causes the grinding of the work to keep the wheel dressed 55 to the same general contour at all times.

55 By changing cams, a variety of shapes may be ground on the ends of various sizes of tappets and pieces. This makes the machine universally adapted for work that would otherwise have to 60 be ground on several different special machines.

65 The design of the machine is such that by adding additional grinding wheel units at various locations around the turntable, the work may be rough ground, semi-finished ground, and finished 65 ground, in one revolution of the turntable.

70 Having thus revealed this invention, I claim as new and desire to secure the following methods, combinations and elements, or equivalents thereof, by Letters Patent of the United States. 70

I claim:

75 1. A grinding or polishing machine of the class described comprising, a stationary base having a track therein, a sliding base having means slidable on said track, a grinding wheel 75

revolvably mounted upon said sliding base, a motor attached to the wheel for driving the same, said grinding wheel revolving about a horizontal axis, a turntable revolving about a vertical axis, revolvably chuck means mounted near the outer edge of said turntable, the prolongation of the chuck axis passing substantially through the axis of the grinding wheel and also, when the turntable is turned to one of its positions, passing along one side of the grinding wheel, spring means for urging the sliding base towards the turntable, and cam means for limiting the amount of said sliding movement, said cam means being of such contour as to cause a slight engagement between the object which is held in said chuck and is being ground or finished for the purpose described and the grinding wheel.

2. A grinding machine as set forth in claim 1 in which the cam means is so shaped as to cause abrupt separation of the sliding base and the turntable when the turntable passes that point where the chuck axis is in alignment with the side of the grinding wheel.

3. A machine of the class described in claim 1 in which constant speed motor driven means is provided for rotating the said chuck.

4. In combination, a base, a second base slidably mounted thereon, a horizontal shaft on the second base at right angles to the direction of sliding movement, a grinding wheel on said shaft, a horizontal turntable, means to drive the same, a work carrier on said turntable, said carrier, in one position, holding the work at right angles to the peripheral face of the wheel, cam means on the second base, follower means on the turntable, spring means urging engagement between the cam and its follower, the shape of the cam and its follower being such as to substantially cause the same degree of engagement along the face of the wheel until the right angled position is reached, and then to cause a separation between the wheel and the article which is being finished or ground.

5. A combination as set forth in claim 4 in which the axis of the turntable lies on a pro-

longation of a plane passing along one side of the grinding wheel.

6. A combination of elements as set forth in claim 4 in which the axis of the turntable is vertical and in which the turntable has a plurality of work carriers mounted thereon and a cam follower comprising a roller located underneath each of the carriers.

7. A combination of elements as set forth in claim 4 in which the cam and its follower causes separation of the wheel and the article prior to said right angled position.

8. A machine of the class described comprising a grinding wheel revolvably mounted on a movable base, means for revolving the wheel, said grinding wheel revolving about a horizontal axis, a turntable revolving about a vertical axis, revolvably chuck means mounted on said turntable, the prolongation of the axis of the chuck means passing through the axis of the grinding wheel and also, when the turntable is turned to one of its positions, passing along one side of the grinding wheel, means for moving the base, relative to the turntable, including a cam and follower, said cam means being of such contour as to cause a slight engagement between the object which is being held in said chuck and the grinding wheel.

9. In a construction of the class described, a turntable turning in a horizontal plane, a series of concentrically positioned chucks thereon, each chuck having its axis radially positioned with respect to the turntable, means for revolving each chuck about its individual axis, a common disc grinding wheel, means for revolving the same, a slideable base for the wheel and its revolving means, said base being so positioned that the terminal edge is substantially along a radius of the turntable and interengaging means between the said movable base and the turntable whereby the work in each chuck is initially engaged on the side of the grinding wheel and then maintained in engagement completely thereacross for the purpose described.

RALPH W. OSBORN. 45
